UNITED STATES PATENT OFFICE.

JAMES D. CARR, OF SAUK CENTRE, MINNESOTA.

WASHING-MACHINE POUNDER.

SPECIFICATION forming part of Letters Patent No. 250,202, dated November 29, 1881.

Application filed July 28, 1881. (Model.)

To all whom it may concern:

Be it known that I, JAMES D. CARR, a citizen of the United States, residing at Sauk Centre, in the county of Stearns and State of Minnesota, have invented certain new and useful Improvements in Washing-Machine Pounders; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to that class of washing-machines in which the cleansing of the clothing is effected by means of a pounder or series of pounders.

It consists in a main frame or carriage movable horizontally on the upper edges of the suds-box, a secondary or pounder frame placed within and movable vertically in the main frame, and a series of pounders arranged within the secondary or pounder frame and operated by a crank, and having their lower ends held in guides, all of which will be hereinafter fully explained, and pointed out in the claims.

In the drawings, Figure 1 is an end elevation of a rectangular suds-box having the end wall or board removed to show the position of the pounders and frames arranged therein. Fig. 2 is a cross-section of the secondary frame and the main frame. Fig. 3 is a view of the under side of the main frame or carriage, and Fig. 4 shows parts of the secondary frame.

a is the suds-box, made rectangular in form and of any desired length. On the upper edges of its longer sides *a'* there are provided small projecting lips or flanges *a'*, which serve as guides to give steadiness to the movement of the pounder-carriage.

b is the carriage, composed of the two sliding bars *b'* and the two cross-bars *b''*, all united to form a strong and substantial frame which moves from end to end of the suds-box in the operation of the machine.

b' are flanges attached to the sides of the sliding bars, and bent so that they catch under the flanges *a'* and hold the frame *b* so that it cannot be lifted vertically from the suds-box. The flanges *b'* do not interfere with the free

back-and-forth movement of the carriage over the suds-box. These guides and flanges may be dispensed with altogether; but I prefer to use them, for by their use less care is required on the part of the operator, as will be herein-after more fully shown.

b'' are anti-friction rollers journaled in suitable mortises in the under edges of the sliding bars *b'*, and arranged to bear on the upper edges of the sides of the suds-box and give freer movement to the carriage.

b'' are vertical guides or grooves arranged at the inner angles formed by the sliding bars and the cross-bars of the frame or carriage *b*, and are adapted to support the pounder-frame in its vertical position and give it steadiness in its vertical adjustment.

c is the pounder or secondary frame, composed of the vertical side bars, *c'*, and the guide-bar *c''*, fixed to the lower ends of the side bars, and provided with a series of vertical guide-openings, *c''*. The upper ends of the side bars are connected by the cross-brace *c''* to give it strength. The frame *c* slides vertically in and is held steadily in place by the guideways provided by the guides *b''* on the carriage *b*, and is carried by the latter from end to end of the suds-box.

d is crank-shaft, journaled in and near the upper ends of the side-bars *c'* of the vertically-adjustable frame *c*. It is provided with a series of wrists, *d'*, arranged on different radii, and so that they give a regular consecutive downward movement to the pounders *e*.

e are a series of pounders, which are connected by arms *e'* with the wrists *d'* on crank-shaft *d*. The arms *e'* pass upward through the guide-holes *c''* in the guide-bars *c''*. The lower ends of the arms, being held in the guide-holes, as shown, will cause an oscillating or walking movement to be imparted to the pounders as the crank-shaft *d* is turned by its crank *d''*. This walking or oscillating movement raises the pounders one after another consecutively, and in the same manner lowers them to the bottom of the suds-box or onto the clothing.

It will be understood that each pounder comes to its lowest point a little in advance of the point touched by the pounder which preceded it, and that as soon as any given pounder is firmly pressed on the clothing the preceding

pounder is lifted. By this construction and arrangement of the several parts the carriage *b*, with the pounder-frame, will be moved from one end of the suds-box to the other by the consecutive action of the pounders on the clothing in the said box. Motion is given to the pounders by turning the crank *d*². The pounders, having been moved to one end of the suds-box, can be moved to the other end by reversing the motion of the crank *d*². By this arrangement the pounders can be kept in motion back and forth over the clothing. The suds-box can be made of any desired length. The adjustable frame *c* is made of suitable material

to give it sufficient weight to impart the necessary pressure to the pounders in washing ordinary clothing. When greater pressure is desired it is given by the hand pressing down on the top brace, *c*⁴; or, if preferred, weights can be laid on the said cross-brace.

It will be seen that the flanges *b*³, catching under the lips *a*², hold the carriage *b* steadily in place and prevent tilting or other irregular movement; but by placing the hand on one of the cross-bars *b*² or on the top of the frame *c* the carriage can be held in place and the pounders kept properly to their work and moved to and fro through the suds-box, as hereinbefore explained. I prefer to use the flanges *b*³ and guides *a*² shown.

The pounder-frame may be lifted from the carriage, and the latter can be slipped off the guides *a*², and both can be placed in the suds-box and be out of the way and protected against injury, when the machine is not in use.

The frame *c* is made adjustable vertically, so that the pounders will automatically adapt themselves to larger or smaller bulks of clothing. If the bulk of clothing was always the same, or was uniform throughout the length of the suds-box, no vertical adjustment would be needed, and the carriage and pounder-frames could be made as a single frame.

It will be seen that the to-and-fro motion of the pounders is automatic, and that this automatic movement brings the entire washing in the suds-box under the influence of the pounders. The same result could be obtained by having the carriage and pounder-frame supported in a stationary frame and the suds-box

arranged on anti-friction rollers, so that it would move easily to and fro under the pounders. The action of the pounders on the bottom of the suds-box or on the clothing will cause the said box to be moved automatically to and fro, and by the turning of a single crank; but this construction requires the very nicest adjustment of the suds-box; otherwise the additional weight of the water and clothes will be hard to overcome by the pressure and walking movement of the pounders. I prefer the construction first hereinbefore described, in which the pounders are moved and the suds-box remains fixed.

Having thus described my invention, what I claim, and desire to secure by Letters Patent, is—

1. The combination, substantially as described, of the suds-box, the horizontally-moving carriage mounted thereon, the crank-shaft provided with a series of cranks, each at right angles with the adjacent crank, vertically-moving bearings, in which said crank-shaft is mounted, and a series of pounders, one mounted on each crank, and having their lower ends held in guides, whereby the pounders are adapted to fall consecutively upon the bottom of and automatically move from end to end in the stationary suds-box, as set forth.

2. The combination, with a stationary suds-box, of a horizontally-moving carriage or frame, *b*, placed on and held by lips or flanges to the top of the suds-box *a*, vertically-movable frame *c*, supported in guides in the frame *b*, a shaft journaled in the upper end of the frame *c*, and having a series of cranks, each arranged at right angles to the adjacent one, and a series of pounders journaled on the cranks, whereby they are adapted to fall consecutively upon the bottom of and automatically traverse from end to end in the suds-box, substantially as set forth.

In testimony whereof I affix my signature, in presence of two witnesses, on this 13th day of July, 1881.

JAMES D. CARR.
